WARREN B. FLANDERS, OF PHILADELPHIA, PENNSYLVANIA, ASSIGNOR TO WESTINGHOUSE ELECTRIC & MANUFACTURING COMPANY, A CORPORATION OF PENNSYLVANIA

TURBINE AND CONDENSER CONSTRUCTION

Application filed February 28, 1931. Serial No. 519,225.

My invention relates to a turbine and condenser construction, and it has for its object to balance the atmospheric pressures on the turbine and on the condenser, so that the condenser may be supported independently of the turbine and connected to the turbine casting by a flexible joint permitting expansion and contraction with temperature changes.

In accordance with my invention, I dispose a condenser beneath the exhaust chamber of the turbine and connect the same thereto by an expansion joint. I connect a pressure-balancing member to the upper side of the exhaust chamber by an expansion joint, 5 and to the condenser by compression struts. The under side of said member is subjected to the absolute pressure within the exhaust chamber, and the downward atmospheric pressure on its upper side is transmitted 10 through the struts to counterbalance the upward atmospheric pressure on the condenser.

The above and other objects are effected by my invention, as will be apparent from the following description and claims taken 15 in connection with the accompanying drawing and forming a part of this application, in which:

Fig. 1 is a side elevation of a turbine and condenser unit in which the compression struts are disposed on the outside of the turbine casing;

Fig. 2 is a plan view of the unit shown in Fig. 1;

Fig. 3 is a vertical sectional view, taken 20 along the line III—III of Fig. 4, and showing a modified construction in which the compression struts are disposed interiorly of the turbine exhaust chamber; and,

Fig. 4 is a horizontal section taken along 25 the line IV—IV of Fig. 3.

Referring now to the drawing more in detail, I show in Figs. 1 and 2, a steam turbine supported in any suitable manner, as by transverse I-beams 11 and 12. The turbine 30 comprises a rotor 13 and a casing 14, the latter including an exhaust chamber 15, through which the motive fluid expanded in the turbine is exhausted from the casing.

The exhaust chamber 15 is formed with an 35 outlet 16, through which the exhaust fluid is

discharged to a condenser 17. The condenser is formed with an inlet 18 which is connected, by means of an annular expansion joint 19, to the outlet 16 of the exhaust chamber. The condenser 17 is rigidly supported on the foundation 20 independently of the turbine, preferably resting on piers 18' and 19'. The condenser carries a hot well 21, which is rigid therewith.

The exhaust chamber 15 is formed with an opening 22 on its upper side which is closed by a pressure-balancing member 23. The latter is connected to the exhaust chamber by an annular expansion joint 24 permitting vertical movement of the member 23 relative to the exhaust chamber. The pressure-balancing member 23 is rigidly connected to the condenser 17 by means of vertical compression struts 25, which are bolted at their lower ends to the condenser and at the upper ends to projections 26 on the member 23. In this embodiment, the struts 25 are disposed outside of the exhaust chamber 15.

The exhaust chamber 15 is concaved, as shown in Fig. 1, to accommodate the bearing 20'. The concavity extends upwardly a sufficient extent to permit the bearing cover to be removed without disturbing the turbine casting.

In operation, the condenser maintains a 50 vacuum within the steam condensing space of the condenser and within the exhaust chamber 15. The pressure-balancing member 23 is subjected on its lower side to this vacuum and on its upper side to atmospheric pressure, and the resultant downward force is transmitted through the struts 25 to the condenser 17. The cross-sectional areas of the openings defined by the expansion joints 19 and 24 are equal, so that the downward force 55 transmitted from the member 23 through the struts 25 will completely counterbalance the atmospheric pressure biasing the condenser 17 upwardly.

From the above description, it will be seen 60 that I have provided a construction wherein the atmospheric pressures on the turbine and on the condenser are balanced, so that the condenser may be supported independently of the turbine and connected thereto by a 65

flexible joint, without subjecting either the condenser or the turbine to atmospheric pressure tending to displace the same.

In the construction shown in Fig. 3, compression struts 27 are extended within the interior of the exhaust chamber. They are disposed adjacent to the wall of the chamber on opposite sides of the rotor shaft 13' and are curved to conform to the shape of said wall. In this form, the struts do not provide any substantial hindrance to the flow of the exhaust fluid.

In order to facilitate assembly and disassembly of the turbine casing, which is divided along the horizontal plane of the turbine axis as indicated at 28, the struts 27 are each divided adjacent said plane as indicated at 29, forming upper parts 31 and lower parts 32. The upper parts are secured to the pressure-balancing member 23, being preferably integral therewith and the lower parts 32 are made integral with the condenser inlet connection 33. Since the struts transmit compression stresses, it is not necessary to rigidly connect the parts 31 and 32, it being sufficient to abut them as shown at 29.

In order that the upper and lower parts of the struts may be held by the upper and lower parts of the casing, respectively, during assembly and disassembly, screws 34 are inserted through slots 35 in the parts of the struts and secured in the wall of the chamber. The slots 35 are of sufficient vertical extent to permit free vertical movement of the struts relative to the exhaust chamber.

It will be seen, therefore, that I have provided a further embodiment in which the struts do not interfere with the flow of the exhaust fluid, and which do not require any bolting or unbolting other than that in connection with the casing proper. The operation of the pressure-balancing member 23 and the struts in balancing the atmospheric pressure on the condenser is identical with that of Figs. 1 and 2.

While the expansion joints preferably define equal areas, as disclosed in the above embodiments, so that the atmospheric pressure on the pressure-balancing member completely balances the otherwise unbalanced atmospheric pressure on the condenser, it will be apparent that the benefits of the invention are obtained in any construction of the character disclosed in which the atmospheric pressure on the pressure-balancing member balances any substantial amount of the otherwise unbalanced atmospheric pressure on the condenser.

While I have shown my invention in two forms, it will be obvious to those skilled in the art that it is not so limited, but is susceptible of various other changes and modifications, without departing from the spirit thereof, and I desire, therefore, that only such limitations shall be placed thereupon

as are imposed by the prior art or as are specifically set forth in the appended claims.

What I claim is:

1. The combination of a turbine casing having an exhaust chamber, a condenser disposed below the exhaust chamber, an expansion joint connecting the condenser to the exhaust chamber, a pressure balancing member disposed above the exhaust chamber, an expansion joint connecting the pressure balancing member to the exhaust chamber, and means for connecting the condenser to the pressure-balancing member for balancing the atmospheric pressures on the condenser and the pressure-balancing member. 70 78

2. The combination of a turbine exhaust chamber having upper and lower openings of substantially equal areas, a condenser disposed beneath the exhaust chamber, an expansion joint connecting the condenser inlet with said lower opening, a pressure-balancing member, an expansion joint connecting the pressure-balancing member with said upper opening, and means for transmitting the downward force of the atmospheric pressure on said pressure-balancing member to the condenser to balance the upward force of the atmospheric pressure on the latter. 80 85 90

3. The combination of a turbine exhaust chamber having upper and lower openings of substantially equal areas, means for supporting the exhaust chamber, a condenser disposed beneath the exhaust chamber, means for supporting the condenser independently of the exhaust chamber, an expansion joint connecting the condenser inlet with said lower opening, a pressure-balancing member, an expansion joint connecting the pressure-balancing member with said upper opening, and means for transmitting the downward force of the atmospheric pressure on said pressure-balancing member to the condenser to balance the upward force of the atmospheric pressure on the latter. 95 100 105

4. The combination of a turbine exhaust chamber having upper and lower openings of substantially equal areas and disposed in horizontal planes, means for supporting the exhaust chamber, a condenser disposed beneath the exhaust chamber, means for supporting the condenser independently of the exhaust chamber, an expansion joint connecting the condenser inlet with said lower opening, a pressure-balancing member, an expansion joint connecting the pressure-balancing member with said upper opening, and means for transmitting the downward force of the atmospheric pressure on said pressure-balancing member to the condenser to balance the upward force of the atmospheric pressure on the latter. 110 115 120

5. The combination of a foundation, a turbine casing having an exhaust chamber and supported on said foundation, a condenser disposed below the exhaust chamber, an ex- 125 130

pansion joint connecting the condenser to the exhaust chamber, a pressure-balancing member and an expansion joint connecting the same to the upper side of the exhaust chamber, said member being subjected on its upper side to atmospheric pressure and on its lower side to the absolute pressure in the exhaust chamber, and a compression member between the pressure-balancing member and the condenser for transmitting the downward atmospheric pressure on the pressure-balancing member to the condenser to balance the upward atmospheric pressure on the latter.

6. The combination of a foundation, a turbine casing having an exhaust chamber and supported on said foundation, a condenser disposed below the exhaust chamber, an expansion joint connecting the condenser to the exhaust chamber, a pressure-balancing member and an expansion joint connecting the same to the upper side of the exhaust chamber, said member being subjected on its upper side to atmospheric pressure and on its lower side to the absolute pressure in the exhaust chamber, and struts for transmitting the downward atmospheric pressure on the pressure-balancing member to the condenser to balance the upward atmospheric pressure on the latter, said struts being disposed within the exhaust chamber adjacent the wall thereof and conforming to the shape of said wall to minimize hindrance to flow of fluid through the exhaust chamber.

7. The combination of a foundation, a turbine casing having an exhaust chamber and supported on said foundation, said casing being divided on the plane of the turbine axis, a condenser disposed below the exhaust chamber, an expansion joint connecting the condenser to the exhaust chamber, a pressure-balancing member and an expansion joint connecting the same to the upper side of the exhaust chamber, said member being subjected on its upper side to atmospheric pressure and on its lower side to the absolute pressure in the exhaust chamber, and a compression member between the pressure-balancing member and the condenser for transmitting the downward atmospheric pressure on the pressure-balancing member to the condenser to balance the upward atmospheric pressure on the latter, said compression member being divided adjacent said plane of division into two parts to facilitate assembly and disassembly of the turbine, one of said parts being attached to the pressure-balancing member and the other to the condenser.

In testimony whereof, I have hereunto subscribed my name this 27th day of Feb., 1931.

WARREN B. FLANDERS.
